UNITED STATES PATENT OFFICE.

WILLIAM E. SHERWOOD, OF CANASTOTA, NEW YORK.

FLEXIBLE-RUNNER SLED.

1,281,859.

Specification of Letters Patent. Patented Oct. 15, 1918.

Application filed August 29, 1916. Serial No. 117,427.

To all whom it may concern:

Be it known that I, WILLIAM E. SHERWOOD, a citizen of the United States, and a resident of Canastota, in the county of Madison and State of New York, have invented a certain new and useful Flexible-Runner Sled, of which the following is a specification.

This invention relates to sleds which are steered by flexing the runners thereof, and it has for its object a particularly simple and efficient construction by which the runners are flexed; and the invention consists in the combinations and constructions hereinafter set forth and claimed.

In describing this invention reference is had to the accompanying drawings in which like characters designate corresponding parts in all the views.

Figure 1 is a side elevation of a sled embodying my invention.

Figs. 2 and 3 are inverted plan views thereof, the positions of the runners and the benches being shown when the runners are straight or unflexed in Fig. 2 and when the runners are flexed in one direction in Fig. 3.

Figs. 4 and 5 are detail views of the front and rear benches and contiguous parts.

The sled comprises generally a body, flexible runners, and means for flexing adjacent portions of each runner so that the middle section between the benches and the front portion in front of the front bench are displaced laterally in opposite directions.

1. designates the body of the sled; 2 the flexible runners, and 3, 4 front and rear benches mounted on the runners. The front and rear benches are mounted so that the runners between the benches can warp in a direction opposite to that in which the front ends of said runners are flexed so as to give a maximum curvature to the runners. For instance, as seen in Fig. 3 the front ends of the runners are flexed to the left or upwardly on the sheet while the portions of the runners between the benches 3, 4 are bowed to the right or downwardly, hence the portions of the runners resting on the ground 50 are flexed so that a comparatively large steering movement is obtained.

In this embodiment of my invention, the front benches are pivoted to the body or the cross bar 5 thereof on vertical axes located to the inside of, that is, between the runners, and are secured to the cross bar 5 by

means of pins 6, 7 passing through arc-shaped slots 8, 9 the pins having enlarged heads or washers overlying the slots so as to hold the benches in position. During the warping or flexing of the runners, each bench moves about an axis located somewhere between the two slots, and the pins and slots guide the benches in their turning movement.

65

The rear benches 4 are also pivotally connected to the body or cross bar 10 thereof, and as here shown, the pivotal pins are located to the outside of parallel lines running lengthwise of the sled and intersecting the pivotal points of the front benches. The rear benches are here shown as pivoted at 11 in vertical lines intersecting the runners. These rear benches are secured in position by pins 12 similar to the pins 6, 7, the pins 75 12 passing through arc-shaped slots 13 concentric with the axes 11.

The means for turning or flexing the runners is connected to the front ends of the runners and also to the front benches 3. 80 This steering means as here shown comprises a lever 14 preferably extending lengthwise of the sled midway between the front ends of the runners and pivoted at 15 to a cross bar 16 connecting the front ends 85 of the runners, parts against which the rear end of the lever braces so that movement of the lever will cause the pivotal point 15 to move laterally in one direction or the other and hence transmit lateral movement to the front ends of the runners, and a steering member or foot piece 17 connected to the lever 14.

In this embodiment of my invention, the parts against which the rear end of the lever 95 14 braces are push and pull rods 19 to which the lever is pivoted at 18, said rods diverging toward their rear ends and being pivoted at 20 at their rear ends respectively, to the front benches 3.

100

The pivots 20 may be at any suitable points determined by the amount of leverage desired, and the points 20 are usually located between the slots 8, 9 so that they are near the vertical axis of the front benches.

105

In operation, upon the turning of the lever 14 by means of the steering member 17, the pivotal point 15 of said lever is swung laterally in one direction transferring its lateral movement to the front ends of the runners 2, and also the rear end of this lever swings in a small arc as illustrated as in Fig.

110

3 in which it is shown as swinging to the right, the left hand rod 18 is pulled thereby turning the left hand front bench 3 over to the left or in anticlockwise direction by 5 pulling forward on its inwardly extending bracket, and the right hand front bench 2 is moved over to the left or anticlockwise by pushing rearwardly on its inwardly extending bracket. This movement of the brackets 10 causes the parts of the runner between the benches, which parts run upon the ground, to concave in a direction opposite to the flexing movement of the front ends of the runners, this flexing being permitted by reason 15 of the location of the centers 11 of the rear benches and to the fact that both the front and rear benches are permitted to turn.

This sled is particularly advantageous in 20 that by reason of the flexing and the way in which the runners are mounted, the portions 25 of the runners between the benches are flexed as well as the portions in front of the front benches, and further in that the flexing being in two directions more steering effect is obtained than when the flexing is in but one direction.

What I claim is:

1. A sled comprising flexible runners, 30 front and rear benches mounted on the runners, the front benches being mounted to move about vertical axes whereby the runners can flex between the benches, and means for flexing the runners, said means being connected to the front benches to turn the 35 same, substantially as and for the purpose set forth.

2. A sled comprising flexible runners, 40 front and rear benches mounted on the runners, the front benches being mounted to move about vertical axes whereby the runners can flex between the benches and means for flexing the runners, said means being connected to the front benches to turn the same, and to the runners near the front ends 45 thereof, substantially as and for the purpose described.

3. A sled comprising flexible runners, 50 benches mounted on the runners and movable about vertical axes, a steering member movable laterally about an axis from its central position, connections between the steering member and the front ends of the flexible runners, and connections between the steering member and the benches, substantially 55 as and for the purpose specified.

4. In a sled, the combination of flexible 60 runners, benches mounted on the runners and movable about vertical axes, a bar connecting the front ends of the runners, a lever pivoted to the bar, means for turning the lever, and push and pull rods connecting the lever and the benches, substantially as and for the purpose set forth.

5. A sled comprising a body, flexible run- 65

ners and including inwardly extending brackets, means spaced apart for securing the brackets to the body, said means being slidably connected to the brackets whereby the benches and brackets can move about 70 vertical axes located between the fastening means, and means for flexing the runners and moving the benches about their vertical axes, substantially as and for the purpose specified.

6. A sled comprising a body, flexible runners, benches mounted on the flexible runners and including inwardly extending brackets, means spaced apart for securing the brackets to the body, said means being slidably connected to the brackets whereby the benches and brackets can move about vertical axes located between the fastening means, and means for flexing the runners and moving the benches about their vertical axes, said 80 means being connected to the brackets, substantially as and for the purpose set forth.

7. A sled comprising a body, flexible runners, benches mounted on the flexible runners and including inwardly extending 90 brackets, means spaced apart for securing the brackets to the body, said means being slidably connected to the brackets whereby the benches and brackets can move about vertical axes located between the fastening means, and means for flexing the runners and moving the benches about their vertical axes, said means being connected to the brackets, substantially as and for the purpose set forth.

8. A sled comprising a body, flexible runners, benches mounted on the flexible runners and including inwardly extending 100 brackets, means spaced apart for securing the brackets to the body, said means being slidably connected to the brackets whereby the brackets can move about vertical axes, and means for flexing the runners, connected 110 to the front ends of the runners to turn the same laterally and to the benches to turn said benches about the vertical axes of the brackets, substantially as and for the purpose specified.

9. A sled comprising a body, flexible runners, front and rear benches mounted on the runners, the front benches being mounted to move about vertical axes located between the runners, the rear benches being mounted to twist upon vertical axes located outside of lengthwise parallel lines intersecting the axes of the front benches, and means for flexing the runners, substantially as and for the purpose set forth.

10. A sled comprising a body, flexible runners, front and rear benches mounted on the runners, the front benches being mounted to move about vertical axes located between the runners and the rear benches be-

ing mounted to twist upon vertical axes substantially intersecting the runners, and means for flexing the runners, said means being connected to the front ends of the 5 runners to swing the same laterally and to the front benches to turn the same about their vertical axes, substantially as and for the purpose specified.

11. A sled comprising a body, flexible runners, front and rear benches mounted on the 10 runners, the front benches being mounted to move about vertical axes located between the runners and the rear benches being mounted to twist upon vertical axes located

outside of lengthwise parallel lines substantially intersecting the axes of the front benches, and means for flexing the runners, said means comprising a member connecting the front ends of the runners, a lever pivoted to said member, and rods pivoted to the 20 rear end of the lever and to the front benches, substantially as and for the purpose set forth.

In testimony whereof I have hereunto signed my name, at Syracuse, in the county 25 of Onondaga and State of New York, this 17th day of February, 1916.

WILLIAM E. SHERWOOD.
